[57] **CLAIM**

The ornamental design for a bottle cage, as shown and
described.

DESCRIPTION

FIG. 1 is a front elevational view showing the ornamental
appearance of my bottle cage;

FIG. 2 is a left side elevational view of the bottle cage
depicted in FIG. 1, the right side elevational view being a
mirror image thereof;

FIG. 3 is a rear elevational view of the bottle cage depicted
in FIG. 1;

FIG. 4 is a bottom plan view of the bottle cage depicted in
FIG. 1; and,

FIG. 5 is a top plan view of the bottle cage depicted in FIG.
1.
